Inventor:

H. P. Chapman

By his Attorney

John E. Earle

United States Patent Office.

H. P. CHAPMAN, OF ESSEX, ASSIGNOR TO THE CENTRE BROOK MANUFACTURING COMPANY, OF CENTRE BROOK, CONNECTICUT.

Letters Patent No. 97,166, dated November 23, 1869.

IMPROVEMENT IN EXTENSION-BIT.

The Schedule referred to in these Letters Patent and making part of the same.

To all whom it may concern:

Be it known that I, H. P. CHAPMAN, of Essex, in the county of Middlesex, and State of Connecticut, have invented a new Improvement in Extension-Bits; and I do hereby declare the following, when taken in connection with the accompanying drawings, and the letters of reference marked thereon, to be a full, clear, and exact description of the same, and which said drawings constitute part of this specification, and represent, in—

Figure 1, a front view;

Figure 2, a side view; and in

Figure 3, a perspective view, in which the fixed cutter is constructed to throw the chips back.

This invention relates to an improvement in extension-bits, that is to say, bits constructed with an adjustable cutter, so as to bore holes of different sizes; and

The invention consists in constructing the adjustable cutter with a slot, the two edges of which are inclined, and so as to receive a conical-headed set-screw, the conical head of the screw tending to open the slot, so as to fix the cutter in its seat; also, in constructing the fixed cutter of a gouge shape, and so as to throw the chips either to the front or rear of the adjustable cutter.

To enable others skilled in the art to make and use my invention, I will proceed to describe the same, as illustrated in the accompanying drawings.

A is the shank, or spindle of the bit, constructed with a head, B, the lower end of which is rounded, or spherical shape, and in the said rounded end a lip, *a*, is formed, which serves as the cutter, and makes what we term a gouge-lip, the whole terminating in a pointed screw, *d*.

C is the adjustable cutter, constructed with a slot, *f*, opening from one side, and, by preference, nearer the upper than lower edge, as seen in fig. 1.

Upon the lower edge, the cutting-lip *h* is formed, as also a spur, *i*, the cutter and spur being of common construction.

The slot *f* is inclined upon its edges, as seen in figs. 1 and 2, and so as to receive the conical head of the

set-screw *D*, which is turned into the head *B* of the bit, so as to draw down into the slot, and press the cutter *C* to its seat.

The cutter, being placed in a groove or slot formed in the face of the head, the tendency of the conical screw-head is to open the slot *f*, and thus wedge the cutter between the upper and lower edge of the groove or slot in the head of the bit. By this means, the cutter is held in the firmest manner, and the construction is extremely simple.

If preferred, and in large bits it may be advisable, the upper and lower edge of the groove or slot in the head may be made of dovetailed form, or with a lip to overlap the cutter, and the edges of the cutter constructed accordingly, and thus aid in the holding of the cutter; but such construction is not essential, as I find, in practice, the slot *f*, with the conical screw, to be all sufficient.

The lip *a* may be constructed on either side, that is to say, as in fig. 2 or fig. 3, so as to throw the chips either to the front or rear.

I am aware of the patents of W. A. Ives, October 13, 1868, and W. A. Clark, May 11, 1858, reissued June 22, 1868, and do not wish to be understood as claiming anything found in the two patents.

Having fully described my invention,

What I claim as new and useful, and desire to secure by Letters Patent, is—

1. The head or fixed cutter, constructed so as to form a gouge-lip or cutter, *a*, in combination with a cutter, *C*, made adjustable in the head above said gouge-lip *a*, substantially as set forth.

2. In adjustable bits, the cutter *C*, when constructed with the slot *f*, with its inclined edges, and combined with the conical-headed set-screw *D*, so that the said screw will spread each side from the slot, to bind the cutter into its seat, substantially in the manner and for the purpose set forth.

H. P. CHAPMAN.
